UNITED STATES PATENT OFFICE.

TECKLAN ARNESON, OF CLARKS GROVE, MINNESOTA.

DOOR-LATCH.

1,178,699.

Specification of Letters Patent. Patented Apr. 11, 1916.

Application filed May 14, 1913. Serial No. 767,590.

To all whom it may concern:

Be it known that I, TECKLAN ARNESON, a citizen of the United States, residing at Clarks Grove, in the county of Freeborn and State of Minnesota, have invented certain new and useful Improvements in Door-Latches, of which the following is a specification.

This invention relates to improvements in door latches and more particularly to a latch adapted primarily for use on barn doors, poultry houses and the like and its object is to produce a device of this class that is simple in construction and efficient in operation.

With the foregoing and other objects in view the invention consists in the combination and arrangement of parts to be herein-after fully described in the following specification, pointed out in the claims and illustrated in the accompanying drawing which forms a part of said specification and in which—

Figure 1 is a front elevation of my improved latch in position. Fig. 2 is a section taken on line 2—2 of Fig. 1. Fig. 3 is a section taken on line 3—3 of Fig. 1. Fig. 4 is a section taken on line 4—4 of Fig. 1. Fig. 5 is a perspective view of the angular plate employed, the barn and barn door being shown in section.

Like reference characters indicate corresponding parts throughout the several views.

1 is the barn door or poultry house door to which my latch is applied and 2 is the barn or house. To the outside of the barn door a latch bar 3 is pivoted upon a bolt 4 which bolt also pivotally carries a reach bar 5 disposed inside the barn door parallel with the said latch bar. The opposite end of the reach bar is apertured to permit passage therethrough of a threaded handle 6 which also passes through an elongated aperture 7 in the barn door and through an aperture in the aforesaid latch bar and the purpose of which is to oscillate the latch bar in the apertured portion of the barn door.

8 is the ordinary apertured guide plate secured to the barn door and through which the latch bar passes and 9 the keeper carried by the barn and adapted for releasable locking engagement with the latch bar for holding the said door fast in its closed position.

10 is an angular plate secured to the barn

door and in the looped end of the same the locking lever 11 is pivoted which is formed with a shoulder 11^a so formed as to lie immediately above the latch bar when both members 11 and 3 are in closed or associated relation, said shoulder 11^a then abutting the barn wall as shown in full lines in Fig. 2; the said lever 11 is adapted for engagement with the latch bar to retain the same in engagement with the keeper 9 and is in frictional contact with the free extremity of a flat spring 12 secured to the angular plate 10, whereby said lever is retained in operative position. An aperture 13 is provided in the barn and through the same the body of a spring-pressed bolt 14 extends for contact with the lever 11, the spring and head of said bolt being disposed upon the inside of the barn and the purpose of said bolt being to permit movement of the latch from the inside of the barn. By striking a blow upon the head of the spring-pressed bolt the same forces the lever 11 out of engagement with the latch bar against the pressure of the spring 12 and then by raising the said latch bar out of engagement with the keeper 9 by means of the handle 6 past the shoulder 11^a the door may be opened from the inside of the barn. From the outside of the barn the lever 11 may be manually raised against the tension of its spring 12 and the latch bar raised out of engagement with the keeper 9 and the door opened.

What is claimed is—

1. A latch comprising a latch bar and a reach bar, a pivot connecting said members, a handle connecting said members, a keeper, a pivotally supported locking lever for engagement with said latch bar, a flexible member carried by the supports of said locking lever in engagement with said lever to yieldably retain it in engagement with said latch bar, and flexible means disposed adjacent said locking lever capable of contact therewith whereby said lever may be disengaged from said latch bar to permit the same to be raised out of said keeper.

2. A latch comprising a latch bar and a reach bar, a pivot connecting said members, a handle connecting said members, a keeper for said latch bar, a pivotally supported locking lever for engagement with said latch bar, a spring carried by the supports of said locking lever in engagement with said lever to yieldably retain it in engagement with said latch bar, and a spring-pressed bolt dis-

posed adjacent said locking lever capable of contact therewith whereby said lever may be disengaged from said latch bar to permit the same to be raised out of said keeper by 5 the aforesaid handle.

In testimony that I claim the foregoing as my own I have hereto affixed my signa-

ture in the presence of two subscribing witnesses.

MR. TECKLAN ARNESON.
